Patented Sept. 21, 1971

221,973

PEANUT VINE CUTTER OR THE LIKE

Louis C. Johnson, Box 49, Pendleton, N.C. 27862

Filed Sept. 8, 1969, Ser. No. 19,051

Term of patent 14 years

Int. Cl. D15—03

U.S. Cl. D40—1

Fig 1

Fig 3

FIG. 1 is a perspective view of my peanut vine cutter or the like, showing my new design;

FIG. 2 is a side elevational view of such cutter; and
FIG. 3 is an opposite side elevational view thereof.

I claim:

The ornamental design for a peanut vine cutter or the like, as shown.
